UNITED STATES PATENT OFFICE.

ENRICO FEROLDI, OF TURIN, ITALY.

CARBURETER.

1,322,554.

Specification of Letters Patent. Patented Nov. 25, 1919.

Application filed November 3, 1917. Serial No. 200,022.

To all whom it may concern:

Be it known that I, ENRICO FEROLDI, subject of the King of Italy, and resident of Turin, Italy, have invented certain new and 5 useful Improvements in Carbureters, of which the following is a specification.

This invention has for its object an arrangement for modifying the composition of the mixture supplied by the carbureters in 10 order to obtain the best percentage of its constituents (fuel and air) in accordance with the running speed of the engine and atmospherical and barometrical conditions; said arrangement comprises a device opening a suitable air inlet when the member controlling the supply of mixture to the engine 15 is fully opened so that the richness of the mixture may be reduced the supply of air being suitably increased.

Such an arrangement may be constructed in various manners according to the type of the carbureter to which it is to be applied and is preferably operated by the member controlling the mixture supply to the engine, 20 this allowing of making as simple as possible its operation which may be effected by the same member controlling the valve of the carbureter.

The annexed drawing shows by way of 25 example some constructions of said device and Figure 1 shows diagrammatically a construction of the same as applied to a butterfly valve carbureter; Fig. 2 shows in section another construction for carbureters of the 30 same type; Fig. 3 is the outer view of the same at 90° with regard to the section shown in Fig. 2.

In the construction shown in Fig. 1, a portion of the wall of the chamber 1, into 35 which the fuel supplied by nozzle 2 is atomized, is shaped to form the seat 1' for a valve 3 the stem 4 of which is mounted so as to reciprocate in a hole of the seat and extends into the chamber 1. The valve seat is 40 pierced by holes 5 and is provided with a cap 6 having holes 7 and carrying a spring 8 intended to push the valve head in its closed position. An adjusting screw 9 mounted in the central portion of cap 6 allows of 45 regulating the stroke of the valve.

The position of the valve seat on the chamber 1 and the length of stem 4 must be 50 properly selected so that the butterfly valve 10 may reach the end of the stem and push the valve away from its seat just when butterfly valve has reached its fully opened

position and is passing beyond the same, as shown in dotted lines.

Obviously with the above described arrangement the carbureter operates in the 60 ordinary manner so long as the butterfly valve 10 is in an intermediate or in its fully opened position, that is in the position in which it is placed along the axis of chamber 1; on the contrary on further operating the 65 controlling lever in the direction required for opening said valve just as this latter is passing beyond its fully opened position the valve impinges the end of stem 4 and pushes the valve 3 away from its seat so as to give 70 passage to atmospheric air through holes 5 and 7.

The mixture produced in the chamber 1 is thus added with air flowing into the chamber owing to the suction exerted by the engine, 75 the depression being thus reduced in the same chamber and consequently the supply of fuel fed by the nozzle 2 being also reduced.

The same result may be obtained by the 80 construction shown in Figs. 2 and 3 in which a seat 1' having holes 5 is provided at the point of wall of chamber 1 in which is journaled one of the pivots of the valve 10; on an extension 11 of said pivot is secured a 85 disk 3' pushed against the seat by a spring 8' and having at its periphery two transverse pivoted rollers 12 each of which is intended to engage a wedge projection 13 provided on the outer wall of chamber 1 90 when the disk 3' and valve 10 reach the required position. Said rollers 12 come into engagement with projections 13 as soon as the valve 10 is passing beyond its fully 95 opened position so that by further rotating said valve by means of the controlling lever 10', the disk 3' is removed from its seat owing to the engagement of rollers 12 with the wedge projections 13 and uncovers holes 5 through which air flows into chamber 1. 100

What I claim as my invention and desire to secure by United States Letters Patent is:—

1. In a carbureter for explosion engines, a carbureting chamber, a throttle valve controlling the communication of said chamber with the engine suction duct formed with auxiliary air openings therein, a valve independent of the throttle valve and maintained by a spring in position to close said openings, and means on said valve adapted to lift the same, said means coöperating with the 105 110

throttle valve only when said throttle valve reaches its fully open position.

2. In a carbureter for explosion engines, a carbureting chamber, a butterfly valve controlling the communication of said chamber with the suction duct of the engine, an auxiliary air valve independent of the said butterfly valve, a pin projecting from said auxiliary air valve and arranged in the path of

said butterfly valve which coöperates with 10 said pin only when said butterfly valve reaches its fully open position.

Signed at Turin, Italy, this 15 day of October, A. D. 1917.

ENRICO FEROLDI.
